UNITED STATES PATENT OFFICE.

MAX E. CRANDALL, OF KINGFISHER, OKLAHOMA.

VALVE-ACTUATING MECHANISM.

Application filed April 9, 1924. Serial No. 705,815.

To all whom it may concern:

Be it known that I, MAX E. CRANDALL, a citizen of the United States, residing at Kingfisher, in the county of Kingfisher and State of Oklahoma, have invented certain new and useful Improvements in Valve-Actuating Mechanism, of which the following is a specification:

This invention relates to an improved valve actuating mechanism for internal combustion engines and seeks, as one of its objects, to provide a mechanism for use in connection with overhead valves and wherein the usual tappets, push rods and rockers will be eliminated.

The invention seeks, as a further object, to provide a mechanism employing a single pull rod for opening each valve.

And the invention seeks, as a still further object, to provide a novel guide for mounting each pull rod.

Other and incidental objects will appear hereinafter.

In the drawings:

Figure 1 is a sectional view showing an engine equipped with my improved mechanism;

Figure 2 is an enlarged detail sectional view on the line 2-2 of Figure 1, looking in the direction of the arrows;

Figure 3 is a detail sectional view showing the joint between the sections of the pull rod employed;

Figure 4 is a view partly in elevation and partly in section, showing a slight modification of the invention, and

Figure 5 is a view similar to Figure 4, showing a further slight modification.

Referring now more particularly to Figures 1, 2 and 3 of the drawings, I have illustrated a conventional engine embodying a crank case 10 upon which is mounted a cylinder 11 and journaled through the crank case is a crank shaft 12 to which is attached a connecting rod 13 extending from a piston 14 slidable in the cylinder. Extending through the cylinder at its upper end is a valve cage 15 mounting a valve 16 and surrounding the valve is a spring 17 cooperating with a cap 18 for normally holding the valve closed. The usual cam shaft of the engine is indicated at 19. All of this structure is of conventional design and need not be further taken up in detail.

Coming now more particularly to the subject of the present invention, I employ a pull

rod which may be formed as a single unit or, as shown in the drawings, may be formed of complementary sections 20 and 21. As shown in detail in Figure 3, one of the sections is formed with a stud 22 while the other of said sections is provided with a socket to accommodate said stud and screwed through the latter section to engage the stud are set bolts 23 connecting the sections. In thus forming the pull rod in sections, the rod may be more conveniently installed and, as will be observed, the section 20 is formed to extend freely through a suitable opening at the top of the crank case 10 while at its adjacent end, the said section is provided with a laterally directed arm 24 to extend beneath the cam shaft 19 for engagement by one of the cams thereon. The section 21 of the rod is curved laterally at its upper end portion to extend over the valve 16 and adjustable upon the section at its upper end is a screw 25 to cooperate with the valve stem, the screw being secured in adjusted position by a nut 26.

Bolted to the crank case 10 behind the pull rod is an upstanding angle plate 27 against which the pull rod abuts and, preferably, the pull rod is of the cross sectional shape shown in Figure 2, so that the plate thus limits the rod against turning movement. Projecting from said plate are vertically spaced pairs of studs 28 and snugly received between said pairs of studs to fit over the pull rod is a channel-shaped sleeve 29 cooperating with the plate to form a guide for the rod. Extending from end to end of the sleeve are side flanges 30 apertured to freely accommodate the pairs of studs 28 and screwed upon said studs are nuts 31 securing the sleeve in position. Interposed between the sides of the sleeve at the longitudinal edges thereof and the plate 27 are packing strips 32 of felt or the like and, as will be seen, the nuts 31 may be adjusted from time to time for compressing said strips and taking up any wear occurring between the pull rod and the sleeve. Thus, the pull rod will, at all times, be efficiently supported and guided so that, as will now be seen, as the cam shaft 19 is revolved, the pull rod will function to open the valve 16. Preferably, the packing strips 32 are saturated with oil so that, at all times, the bearing surfaces of the pull rod and sleeve may be properly lubricated.

In Figure 4 of the drawings, I have il-

lustrated a slight modification of the invention wherein, instead of employing a single guide for the pull rod, I employ spaced guides 34. These guides are identical with the guide previously described with the exception that the said guides are shorter. As will be observed, the angle plate of the upper guide is bolted or otherwise secured to the upper end of the cylinder so that this guide will effectually serve to support the pull rod near its upper end while the lower guide will likewise support the pull rod near its lower end.

In Figure 5 of the drawings, I have illustrated a still further modification wherein the cam shaft as illustrated at 19 in Figure 1, is eliminated, and in lieu thereof cams such as typically shown at 35, are formed directly upon the crank shaft 36 of the engine. A guide 37 like the guide illustrated and described in connection with Figure 1, is employed, and slidably through the guide is a pull rod 38. The pull rod is identical with the pull rod of the preferred construction with the exception that the pull rod 38 is longer and is provided at its lower end with an elongated arm 39 to extend beneath the crank shaft 36 and cooperate with the cam 35 upon said shaft. Thus, as the crank shaft revolves, the valve at the upper end of the engine cylinder will be opened. This modified structure accordingly also provides a very effective arrangement and a mechanism which, as compared with usual overhead valve mechanisms as now in common use, eliminates not a few parts.

The invention is, of course, capable of various other modifications such, for instances, as variations in shape and cross sectional contour of the pull rod, or in the

exact design of the guide therefor, and I accordingly reserve the right to all such variations as may fall within the spirit of the appended claims.

Having thus described the invention, what I claim is:

1. In an internal combustion engine, a crank case, a cylinder associated therewith, a valve in the head of said cylinder, a plate upstanding from the crank case, a rod extending from the crank case to abut said plate limited thereby against rotation and disposed to coact with the valve for opening the valve, and means for actuating said rod.

2. In an internal combustion engine, a crank case, a cylinder associated therewith, a valve in the head of said cylinder, a rod extending from the crank case to coact with the valve for opening the valve, means for actuating said rod, a plate upstanding from the crank case, a sleeve fitting the rod to cooperate with said plate and form a guide for the rod, and means adjustably connecting the sleeve with said plate.

3. In an internal combustion engine, a crank case, a cylinder associated therewith, a valve in the head of said cylinder, a rod extending from the crank case to coact with the valve for opening the valve, means for actuating said rod, a plate upstanding from the crank case, a sleeve fitting the rod to cooperate with said plate and form a guide for the rod, means adjustably connecting the sleeve with said plate, and a packing interposed between the sleeve and plate.

In testimony whereof I affix my signature.

MAX E. CRANDALL. [L.S.]
